ROLLING MILL DRIVE

Louis W. Falk, Milwaukee, Wis., assignor to The Falk Corporation, Milwaukee, Wis., a corporation of Wisconsin

Application April 12, 1945, Serial No. 587,953

5 Claims. (Cl. 74—681)

1

This invention relates to rolling mill drives. In the rolling of strip steel, and particularly so-called temper rolled steel, it is common practice to pass the material between two pairs of rolls, sometimes arranged in a single stack, the second pair being driven at a speed higher than that of the first pair so as to tension or stretch the material as it passes from the first to the second pair. The two pairs of rolls are commonly mechanically interconnected through intermeshing gears so as to insure the required positive and accurate control of the difference in roll speeds.

The roll speed differential is not large, usually about ten percent or less, but a fine adjustment thereof within that narrow range is highly desirable in order to obtain the particular degree of stretch best suited for the work at hand.

One object of the present invention is to provide a rolling mill drive readily adjustable in a manner to satisfy the above requirements.

Other more specific objects and advantages will appear, expressed or implied, from the following description of a rolling mill drive constructed in accordance with the present invention.

In the accompanying drawings:

Figure 1 is a vertical longitudinal sectional view of a rolling mill drive embodying the present invention.

Fig. 2 is a fragmentary horizontal sectional view thereof taken substantially along the line 2—2 of Fig. 3.

Fig. 3 is an end elevational view with the change gears shown in the same position as in Fig. 2.

Fig. 4 is a diagrammatic view illustrating a different arrangement of change gears.

Fig. 5 is a view similar to Fig. 4 illustrating a change gear arrangement including an idler gear.

Fig. 6 is a fragmentary sectional view taken substantially along the line 6—6 of Fig. 5.

Fig. 7 is a view similar to Fig. 5 illustrating another arrangement of change gears.

The rolling mill drive selected for illustration includes upper and lower parallel shafts 10 and 11 for connection in driving relation with separate upper and lower pairs of rolls, respectively, of a conventional mill of the type hereinabove mentioned.

The lower shaft 11 is journaled in and extends through an appropriate housing 12 and is driven by suitable means such as an electric motor connectable to the rear end 13 thereof.

The upper shaft 10 is also journaled in the

2

housing 12 and is connected in driving relation with shaft 11 through a suitable planetary gear set operable to effect operation of shaft 10 at any of a plurality of selective speeds within a narrow speed range.

The planetary gear set shown comprises a cage 14 supported at opposite ends in appropriate bearings 15 and 16 for rotation about the axis of shaft 10. In this instance the cage is composed of a central section 17 and end heads 18 bolted or otherwise rigidly united thereto, as partially indicated particularly in Fig. 2. The cage 14 provides a revolving support for a pair of planet members, each journaled at opposite ends in bearings 19 and 20 carried by the cage end heads 18, and each comprising a gear 21 integrally connected to a pinion 22 coaxially aligned therewith. Each planet gear 21 meshes with a sun pinion 23 carried by the shaft 10, and each planet pinion 22 meshes with a sun gear 24 coaxially aligned with pinion 23 and supported in bearings 25 and 26 in the cage 14.

The sun gear 24 is connected in driving relation with the shaft 11 and for that purpose shaft 11 is provided with a pinion 27 that meshes with a gear 28, the latter being preferably flexibly connected to sun gear 24 in order to avoid disturbances and wear that might otherwise result from slight misalignment between those gears. In this instance this is accomplished by mounting the gear 28 on a tubular shaft 29 journaled in bearings 30 and 31 in the housing, and by coupling the tubular shaft 29 to an elongated torsion shaft 32 that extends loosely therethrough from the gear 24. A dental coupling of a well known type, such as shown at 33, provides a satisfactory flexible driving connection between the shafts 29 and 32. Shaft 32 is aligned with shaft 10 and carries the sun gear 24.

The several pinions and gears hereinabove specifically mentioned are preferably proportioned so that as the speed of the cage 14 approaches zero, the shaft 10 rotates at a speed approaching the mid-point of its operating range. The arrangement is such that the speed of shaft 10 will be reduced whenever the cage 14 is permitted to rotate in the direction of shaft 10 and increased whenever the cage rotates in an opposite direction. The speed of the shaft 10 may thus be varied and controlled by regulating the speed and direction of rotation of the cage. Although rotation of the cage may be regulated in various ways, a change-speed gear train is preferably employed for this purpose, this gear train serving to connect the cage with the shaft

11, so that the speed of the shaft 10 may always be definitely related to that of shaft 11.

The change-speed gear train shown includes a pinion 34 meshing with a ring gear 35 carried by and rotating with the cage 14. The pinion 34 is carried by a shaft 36 journalled in the housing 12 and carrying a gear 37 that meshes with a pinion 38 on a shaft 39. The shaft 39 is journalled in the housing and projects through the rear end wall 40 thereof. A gear 41 on the projecting end of the shaft 39 meshes with a pinion 42 whose supporting shaft 43 is fashioned to detachably receive either of a pair of intermeshing change gears 44 or 45. In this instance the small gear 44 is shown on shaft 43 while the other larger gear 45 is shown detachably mounted on a shaft 46 which also carries a pinion 47 meshing with a gear 48 on the tubular shaft 29. The shaft 46 is thus permanently connected to the shaft 11 through the gear train 47, 48, 28, and 27.

For a purpose which will hereinafter appear, the shaft 43 is preferably mounted for adjustment about the axis of shaft 39 with pinion 42 in mesh with gear 41 in all positions of adjustment of shaft 43. In this instance the shaft 43 is shown journalled in a barrel 49 carried by the end of plate-like crank 50 which is supported by a hollow hub 51 rotatably supported in the housing end wall 40, the shaft 39 being centered with respect to the supporting hub 51 by an appropriate bearing 52 within the hub.

In the change-speed gear train above described the several gears and pinions are preferably proportioned so that, with the small change gear 44 on shaft 43 and the large change gear 45 on shaft 46, the cage 14 rotates in a direction opposite that of the shaft 10 and at a rate such as to cause the shaft 10 to rotate at a speed closely approximating that of shaft 11. By interchanging the change gears, so that large gear 45 is on shaft 43 and small gear 44 is on shaft 46, the cage 14 may be caused to rotate at a much lower speed to thereby effect a substantial reduction in the rate of rotation of the shaft 10. Additional intermediate speeds of the shaft 10 may be obtained by the use of additional change gears of other sizes. For instance, by replacing the small change gear 44 with a third change gear 53 of a size intermediate that of gears 44 and 45, and by adjusting the shaft 43 and its supporting arm 50 into a position where the gear 53 will mesh with the large gear 45, as indicated in Fig. 4, one intermediate speed of the shaft 10 may be obtained; and by interchanging these gears 53 and 45, so that gear 53 is on shaft 46 and gear 45 is on shaft 43, a lower intermediate speed of shaft 10 may be had.

The rate of operation of the shaft 10 may be further reduced by the use of an idler gear between the change gears. As indicated in Figs. 5 and 6 for instance, an idler gear 54 is shown detachably fixed to a stub shaft 55 journalled in a cage 56 mounted on and projecting rearwardly from the housing end wall 40. In this instance the idler gear 54 is shown meshing with the large change gear 45 on shaft 46, and the shaft 43 and its supporting arm 50 have been adjusted into a position such that the small change gear 44 meshes with the idler gear 54. With this arrangement of gears the cage 14 rotates at the same relatively high speed as when the change gears 44 and 45 are directly engaged, but in an opposite direction (in the same direction as the shaft 10) thereby causing the shaft 75

10 to rotate at a minimum speed substantially below the range of speeds obtainable with the various change gear combinations described in the immediately preceding paragraph.

5 Rotation of the shaft 10 at other speeds higher than the above mentioned minimum are obtainable by the use of a suitable idler gear with any of the several change gear combinations hereinabove described. As indicated in Fig. 7 for 10 instance, an idler gear 54' may be substituted for the idler 54 on shaft 55, the idler 54' being of a size to mesh with the small change gear 44 on shaft 46, and the crank arm 50 being adjusted so that the large change gear 45 on shaft 15 43 meshes with idler 54'. With the gears thus arranged, the cage 14 is caused to operate at low speed in the same direction as that of shaft 10, causing the latter to rotate at a speed higher than the above mentioned minimum but below any speed obtainable without an idler.

20 From the foregoing it will be noted that a heavy duty drive for rolling mills and the like has been provided by which one roll of a mill may be caused to operate at any of a plurality of selected speeds each bearing a definite predetermined relation to the speed of another roll of the mill, and in which a change from one speed to another is readily accomplished by a simple change in a change-gear combination easily accessible and conveniently arranged for the purpose. It will be further noted that although the torque load on each roll driving shaft is heavy, the torque reaction between the planetary cage and the change-speed gear train is only a fraction of the load on the associated roll driving shaft, and since the torque reaction between the change gears is relatively light, they may be and are of small size convenient for handling and therefore easily replaceable.

25 30 35 40 45 50 55 60 65 70 In the planetary gear set shown provision is made for effecting an accurate positional relation between the teeth of both planets and those of the sun gears, so that the total torque transmitted from one sun gear to the other through the planets may be substantially equally divided between the planets. Any minute departure from such a relationship will ordinarily cause one of the planets to sustain substantially the entire torque load to the exclusion of the other and thereby materially reduce the torque transmitting capacity of the planetary system. This precise relationship is made possible by providing for relative adjustment between the coaxial gears 21 and 22 of one of the planets.

55 60 65 70 75 In this instance the several sun and planet gears shown are of the single helical type in order to obtain smooth and quiet gear action characteristic of such gears; and in order to reduce to a minimum the end thrust imposed on each planet, the helix angles of the gears 21 and 22 of each are preferably of the same hand.

When helical gears are employed, the above noted precise positional relation between the teeth of the planets and those of sun gears are obtainable by rendering one of the planet gears axially adjustable relative to its coaxial gear. In this instance the gear 21 of one planet is splined on its supporting shaft, as indicated at 60, for this purpose, and suitable means such as studs 61 coact with a collar 62 to axially position the gear 21 on its shaft.

75 80 85 90 The desired positional relation between the planets and sun gears may be effected in the following manner. With the cage 17 and one of the sun gears 24 fixed against rotation, the other

sun gear 23 is rotated in one direction until its teeth are brought into firm contact with those of the gear 21 of the upper planet (Fig. 1) and until the teeth of the other gear 22 of that planet are brought into firm contact with those of the fixed sun gear 24. Then, while the sun gear 23 is held in the position of last adjustment, the gear 21 of the lower planet is adjusted axially until its helical teeth make firm contact with those of sun gear 23 and react thereon to establish firm contact between the teeth of the connected gear 22 and those of other sun gear 24. The axial adjustment of the pinion 21 must be in a direction such that the resulting reaction thereof on the sun gear 23 urges the latter to rotate in a direction opposite to that of its initial rotation. Thereafter, while the sun gear 23 is still held against rotation, the studs 61 are anchored to the collar 62 to thereby securely fix the connected gear 21 in its position of last adjustment. It will be noted that the above method of adjustment establishes initial contacts between each sun gear and both planets with these contacts so related that no torque can be transmitted from either sun gear through its initial contact with one planet without producing a simultaneous torque reaction through its initial contact with the other planet.

Various changes may be made in the rolling mill drive hereinabove specifically described without departing from or sacrificing the advantages of the invention as defined in the appended claims.

I claim:

1. A rolling mill drive comprising a first shaft connectable in driving relation with a mill roll, a second shaft parallel thereto connectable in driving relation with another mill roll, a third shaft aligned with said first shaft, heavy duty gearing maintaining a definite speed relation between said second and third shafts, heavy duty planetary gearing connecting said first and third shafts, and control means reacting on said planetary gearing for regulating and determining the speed ratio between said mill rolls.

2. A rolling mill drive comprising a first shaft connectable in driving relation with a mill roll, a second shaft parallel thereto connectable in driving relation with another mill roll, a third shaft aligned with said first shaft, heavy duty gearing maintaining a definite speed relation between said second and third shafts, heavy duty planetary gearing connecting said first and third shafts, and adjustable means connected to said third shaft and reacting on said planetary gearing to regulate the speed ratio between said mill rolls.

3. A rolling mill drive comprising a first shaft connectable in driving relation with a mill roll, a second shaft parallel thereto connectable in driving relation with another mill roll, a third

shaft aligned with said first shaft, heavy duty gearing maintaining a definite speed relation between said second and third shafts, heavy duty planetary mechanism connecting said first and third shafts, said planetary mechanism including a relatively low speed rotor, and a gear train connected to said third shaft and reacting on said rotor to control the planetary action of said mechanism, said gear train including relatively high speed change gears effective to regulate and determine the speed of said rotor.

4. A rolling mill drive comprising a first shaft connectable in driving relation with a mill roll, a second shaft parallel thereto connectable in driving relation with another mill roll, a third shaft aligned with said first shaft, heavy duty gearing maintaining a definite speed relation between said second and third shafts, a pair of coaxial gears connected to said first and third shafts respectively, a rotor, a set of planet gears carried by said rotor and engaged with said pair of gears, and means effective to change the rate and direction of operation of said rotor to thereby regulate the speed ratio between said mill rolls.

5. A rolling mill drive comprising a first shaft connectable in driving relation with a mill roll, a second shaft parallel thereto connectable in driving relation with another mill roll, a pair of coaxial gears, one of said gears being connected to rotate with said first shaft, the other of said gears being connected in driving relation with said second shaft, a rotor, a set of planet members carried by said rotor, each of said planet members including a pair of coaxial gears of different diameters each engaged with one of first named pair of gears, and means for controlling said rotor to thereby control the speed ratio between said mill rolls.
